UNITED STATES PATENT OFFICE

JACOB STEINBERG, OF BROOKLYN, NEW YORK

MINE RAILROAD CAR

Application filed November 18, 1927. Serial No. 234,084.

This invention relates to mine cars.

An object of the invention is to provide an improved car for use on mine railroads.

A further object of the invention is to provide a car of the character described in which several parts thereof are separable for packing, and for facilitating assembly.

A still further object of the invention is to provide an improved car of the character described, having a novel sanding mechanism.

A further object of the invention is to provide an improved car of the character described having a novel braking means.

Another object of my invention is to provide a car construction of the character described, which shall be comparatively simple in construction and manufacture and practical and efficient in operation to a high degree.

Other objects of this invention will in part be obvious and in part hereinafter pointed out.

The invention accordingly consists in the features of construction, combinations of elements, and arrangement of parts which will be exemplified in the construction hereinafter described, and of which the scope of application will be indicated in the following claims.

In the accompanying drawings, in which is shown one of the various possible illustrative embodiments of this invention,

Fig. 1 is a bottom plan view of the car, showing the assembly of wheels, and the sanding and braking devices.

Fig. 2 is a side elevational view of a car embodying the invention.

Fig. 3 is an end elevational view of the car, illustrating details of the car construction.

Fig. 4 is a partial longitudinal sectional view of the car body, with a wall removed.

Fig. 5 is a vertical sectional view of a removed wall.

Fig. 6 is a transverse sectional view on the line 6—6 of Fig. 7, while

Fig. 7 is a transverse fragmental sectional view on line 7—7 of Fig. 6.

On the drawings, a car 10 embodying the invention is shown and consists of a body 12, superimposed upon the carriage 14 made up of the wheels 16 and carried on body 12 in a

manner hereinafter described. The body 12 is formed of two side walls 18, and end wall 20, and a front wall 22, all detachably assembled, as hereinafter appears. Carriage 14 has associated therewith, the sanding device 24 and the braking device 26 mounted cooperatively with the wheels 16.

The side walls 18 are formed in a manner similar to the wall 20, as seen from Fig. 5, of a plate 28, having secured at one end thereof the channel 30, the depending flanges 32 of said channel being spaced from the end 34 of plate 28 by means of the blocks 36, 38, all fixed in relation to each other by the rivets 40. The bars 42 are riveted as at 44 along the vertical edges of said plate, said bars extending beyond the bottom end 46 of plate 28 for a purpose hereinafter appearing.

The bottom 48 of the car is made up of the plate 50, flanged at the sides 52, 54, and having the end flange 56 riveted thereto. Butting up against the edge of end flange 56 is a channel 58, through the inner portion of which is received a strap 60, all these parts being secured removably to bottom 48 by means of bolts and nuts 62. Said straps are U-shaped, the arms of the U extending up from the edges of bottom 48, and being adapted to receive in contact therewith the plates 28 of side walls 18, bolts 64 passing through openings in said strap and being secured through aligned openings in said plate by nuts 70. A number of straps 60 of this type are spaced along bottom 48 and side walls 18 in order to securely, but removably, position the side walls 18 with relation to the bottom 48.

A channel member 72 is riveted to the rear end of each side wall, a bar 74 being retained in the hollow of said member by means of the rivets securing member 72 to side wall 18. By this means, groove 76 is provided into which the plate 28 of end wall 20 is adapted to be received, the bar 42 being received in contact with bar 74, and with the flanged edge 78 of channel 72.

Extending along bottom 48 parallel to side walls 18, but spaced from the side edges of bottom 48, is a bar 80. The spacing is sufficient to receive the ends of plates 28 of side walls 18. A similar bar 82 extends par-

allel to the rear edge 84 of bottom 48. Bars 80 and 82 are cut short at the corners of bottom 48 to snugly receive the depending end of the bars 42 secured to plate 28, thus positively positioning the walls with relation to each other.

The front wall 22 is adapted to be assembled with the side walls 18 in a manner similar to end wall 20, said front wall 22 being 10 formed with a pivoted wall 86 to provide an opening 88 through which the car may be cleaned. A suitable latching device 90 is embodied to secure said wall against movement except when desired, and is seen to consist of pivoted arm 92, having bolts 94, 96, pivotally secured thereto on either side of the pivot point and slidably retained against movement by guides 98. On operation of arm 92, these bolts will be extended into 15 notches 100 in end portions 102 of said front wall. If desired, this latching mechanism may be encased, as is preferable, by sheet 104 applied to the front wall.

Detachably secured by bolts 106 to the one 20 side wall 18 and to the edge of front wall 22 is a bracket 108. Said bracket forms one bearing 110 for the shaft 112, which passes through another bearing 114, carried on a bracket 116, similar to bracket 108. A bevel 25 gear 118 is secured on the end of shaft 112 and meshes with another bevel gear 120, carried on the end of a shaft 122, supported in bearings 124, detachably secured to bottom 48, in any well known manner. A set of bevel 30 gears 125 connects shaft 122 with the longitudinal shaft 127 carried in bearings 129 secured to bottom 48. Shaft 127 is threaded at end 126 and is received in a complementary threaded part 128 in the cross-bar 130 carrying the brake shoes 132. Two guide bars 134 are shown to extend rearwardly from cross-bar 130, being received in guides 136 secured to the shaft 138 of the rear set of wheels 16. The cross-bar 130 is formed with cutouts 45 140 to pass over the flanges 142 of wheels 16, so that the shoes 132 may become operative upon the face 144 of said wheels.

The wheels 16 are mounted on shafts 138, the intermediate portions of which are 50 formed of square cross sections, as appears from Fig. 6. Said shafts are supported from the bottom 48 by the V-shaped straps 146, detachably secured to said bottom, and having the U-shaped strap 148 secured therewithin, and contacting the upper surface of shaft 138 to retain said shaft against vertical movement. The wheels 16 may be made up in any usual manner to provide the flange 142 guiding and positioning the wheels on 55 rails 152. A grease cup 154 is mounted in the hub 156 of said wheels for lubricating purposes.

On the side of the car opposite the bracket 108, another bracket 158 of similar construction is secured and has the shaft 160 passing

therethrough to be received in the bracket 162, mounted similarly to bracket 158 at the lower edge of said side. The bevel gear 164 is positioned at the end of shaft 160, a bevel gear 166 meshing with bevel gear 164 and carrying the end of a stub shaft 168. Said stub shaft is rotatably mounted in a bracket 170, secured to bottom 48 and terminates in threaded portions 172, adapted to be received in a threaded opening in the depending arm of an L-shaped bar 178. Said bar is formed with a plurality of openings 180, which, by rotating shaft 160, are brought into communication with similar openings 182 in the bottom of a hopper 184 having an inclined bottom 186, said hopper receiving sand or similar abrasive material from a chute 188 secured to the side of the car by a strap 190. The openings 182 in the bottom of hopper 184 are aligned with nozzles 192 extending from said hopper and secured in position to discharge sand upon the rails 152, when desired.

It will thus be seen that there is provided a device in which the several objects of this invention are achieved, and which is well adapted to meet the conditions of practical use.

As various possible embodiments might be made of the above invention, and as various changes might be made in the embodiment above set forth, it is to be understood that all matter herein set forth or shown in the accompanying drawings is to be interpreted as illustrative and not in a limiting sense.

Having thus described my invention, I claim as new and desire to secure by Letters Patent:

1. In combination, a car having demountable wall sections, straps detachably secured to the bottom of said car and having upstanding portions providing means for supporting the side walls of said car demountably in position, and channels attached to said side walls for slidably receiving side edge portions of the end walls of said car.

2. A mining car comprising a bottom wall, a substantially U-shaped strap having a portion secured to the under side of said wall, and upstanding portions extending from said first portion, side walls supported by said upstanding portions, an angle member secured to an end edge portion of said bottom wall, said member having an upstanding flange, channel members secured to the end edge portions of said side walls and an end wall removably supported by said channel members, the lower edge portions of said end wall engaging said flange.

3. In a mining car, a removable wall therefor comprising a plate, a channel shaped member received over the edge portion of said wall, blocks interposed between said edge portion and the side flanges of said channel, means for securing said channel, plate

and blocks together, a vertical post secured to
said plate and having a portion extending be-
yond the bottom edge portion of said plate
and means slidably engaging the ends of said
5 plate for detachably supporting the same.

In testimony whereof I affix my signature.

JACOB STEINBERG.
